OVEN CONSTRUCTION

Roland W. White, Cleveland Heights, Ohio, assignor to The Colonnade Company, Cleveland, Ohio, a corporation of Ohio

Application March 14, 1940, Serial No. 323,899

7 Claims. (Cl. 219—35)

This invention relates to oven construction.

One of the objects of this invention is to provide an oven construction which will be simple, practical, and thoroughly durable. Another object is to provide a construction of the above character having a minimum of parts, and capable of easy assembly. A further object is to provide a portable construction of the above character which may be easily operated by unskilled labor. Another object is to provide a construction of the above character which will be neat and attractive in appearance but sturdy in construction to withstand hard usage. It is a further object of this invention to provide a practical construction of the above character in which articles of food may be cooked which require the application of different heat effects to different parts thereof. Other objects will be in part obvious and in part pointed out hereinafter.

The invention accordingly consists in the features of construction, combinations of elements and arrangements of parts, all as will be illustratively described herein, and the scope of the application of which will be indicated in the following claims.

In the accompanying drawings in which is shown one of the various possible embodiments of this invention.

Figure 1 is a side elevation of the oven construction;

Figure 2 is a vertical section taken through the oven on the line 2—2 of Figure 4;

Figure 3 is a vertical section taken along the line 3—3 of Figure 2;

Figure 4 is a top plan view of the oven construction with the lid in an open position; and

Figure 5 is a diagrammatical representation of a circuit for the oven construction.

Similar reference characters refer to similar parts throughout the several views of the drawings.

This invention relates to an oven adapted to cook foods which require the application of different intensities of heat to different portions thereof. In some types of foods, such as custards and pies, to obtain proper cooking, the body of the food must be submitted first to a low constant heat. Next, in order to attain the desired appearance and condition of the upper portion of the article of food, it is submitted to an increased and flexibly controlled heat on its top surface. It is a further object of this invention to provide a construction in which the above operations may be performed in a single oven, eliminating excessive handling of the food.

Referring now to Figure 1, the oven comprises a body portion, generally indicated at 10, which is covered by a lid, generally indicated at 11. The oven is preferably mounted on wheels 12 which permit the oven to be used for cooking in an out-of-the-way place, and then, during meal time, it may be moved to a position where it can serve as a heating table from which articles may be served.

As best seen in Figures 2 and 3, the body portion 10 of the oven comprises bottom wall 13, side walls 14 and 15, and end walls 16 and 17. These walls and lid 11 are preferably made of sheet metal and are filled with any suitable insulation material, such as asbestos, the body portion of the oven being water-tight for purposes to be disclosed more fully hereinafter. A supporting plate 17, which separates the body portion of the oven into two parts, lies in a plane parallel to the bottom 10 of the oven and is supported by members 19a, 19b, 19c, and 19d, which are secured to the side walls of the oven in any suitable manner. Plate 17 is further supported by splash plates 20 and 21 (Figures 2 and 4) which separate the lower part of the oven into a series of sections and extend between plate 17 and bottom wall 13.

As may be best seen in Figure 4, plate 17 has a plurality of openings 22a and 22b (Figure 4) formed therein. Openings 22a are preferably made of a size which permits the lower portion of a pie pan 23 (Figure 3) to extend therethrough, the pie pan supporting itself by its flanged edge which rests on supporting plate 17. The smaller holes 22b are adapted to hold smaller containers, such as custard cups 24, in a similar manner (Figure 2).

The lower part of the oven contains a heat-conducting liquid bath, the level of which is maintained slightly below the lower surface of supporting plate 17 (Figure 2). Water may be used for the bath if temperatures of 212° F. or below are desired, and a liquid having a higher boiling point, such as mineral oil, is used for higher temperatures. A gauge 60, positioned in the side 45 of the oven, indicates the depth of the liquid therein, and drainage outlet 31, controlled by valve 32, permits the removal of the liquid from the oven. The liquid bath is heated by a series of heating elements 25a, 25b, and 25c, which are positioned in the sections formed in the lower part of the oven by splash plates 20 and 21 and controlled by a thermostat, the bulb 26 (Figures 2 and 3) of which extends through all of the sections in the lower part of the oven. Thus, by this thermostat, the temperature of the liquid bath is

maintained at any desired degree. Preferably a series of thermometers 45 (Figures 1 and 4) are provided to show the user the temperature of the liquid in each section of the liquid bath in the lower part of the oven.

Referring now to Figure 4, splash plates 20 and 21 are so shaped that they curve around the lower portions of the custard cups and pie pans and separate the lower portions of the oven into sections as described hereinabove. These plates are secured to oven side walls 14 and 15 and preferably have a series of holes 30 (Figure 3) therein along their lower edges which permit the liquid to flow from one section to another to maintain an even level of liquid in the oven. Splash plates 20 and 21 prevent liquid from surging throughout the length of the oven when the bottom of a pie pan or custard cup is placed in the liquid bath by breaking the waves which such action normally causes, and also limit the circulation of the liquid between sections when all of the heating elements are not in use.

Referring now to Figure 4, lid 11, which is hingedly connected to the body portion of the oven by spring hinges 27a and 27b, is raised and lowered by handles 11a and 11b (Figure 1). On the inner face of lid 11 are a plurality of heating members, and, when the lid is closed, the large and small heating members are positioned directly above the large and small openings in supporting plate 17. These heating members preferably comprise a resistance element mounted on a heat reflecting base, and, when current is passing through the elements, radiate heat downwardly into the body portion of the oven.

Referring now to Figure 5, in which is shown the wiring circuit for the heating elements in the lid and the lower part of the oven, conduits 35 and 36 are connected to any suitable source of current by line plug 37. These conduits lead both to the lid-heating members and the liquid-heating elements, and the supply of current to each of these groups is controlled by switches 38 and 39 respectively. The large heating members 40 are connected directly to conduits 35 and 36, and the small heating members 41 are connected to conduit 36 through switches 42. Thus, the operator by switch 38 controls the lid-heating members as a unit, and, furthermore, has individual control of the groups of small heating members through switches 42.

In the lower part of the oven, the flow of current to the liquid-heating elements is controlled by switch 39, thermostat 33, low water cut-off 43 (Figures 1 and 5), and switches 44. Switch 39 governs the liquid-heating elements as a unit, and switches 44, which are positioned on the front of the oven, individually control the elements. Thermostat 33, as pointed out hereinabove, controls the temperature of the liquid bath, and low water cut-off 43, which may be of any desired construction, is adapted to cut off the current leading to the liquid-heating elements as soon as the liquid level falls below a certain point. Thus, the temperature of the liquid bath is effectively controlled.

In operation, the temperature of the liquid in the oven is first raised to the proper degree, and then the containers with the pies, custards, or other food to be cooked therein are placed in supporting plate 17, and lid 11 is closed. The liquid bath, which is in contact with the lower portions of the food containers, transmits heat by conduction from the heating elements to the food containers. The heating members in the lid are

5 turned on when desired and subject the upper portion of the food to heat by radiation, which serves to lightly brown the top surfaces of the pies and custards. Thus food which requires a low constant heat applied to one part and a greater radiating heat to another may be cooked quickly and efficiently in this oven. Furthermore, the oven is readily applicable to use as a heating table, as all of the lid-heating members may be turned off and the temperature of the liquid bath regulated. Thus, in a cafeteria, when not in use for cooking, this oven may be used as a heating table.

It will thus be seen that I have provided a thoroughly practical, efficient, and durable oven construction in which the several objects disclosed hereinabove, as well as many others, have been successfully achieved.

As many possible embodiments may be made of the above invention and as many changes might be made in the embodiment above set forth, all without departing from the scope of the invention, it is to be understood that all matter hereinbefore set forth or shown in the accompanying drawings is to be interpreted as illustrative and not in a limiting sense.

I claim:

1. In apparatus of the character described, in combination, an oven comprising a body portion and a lid, a plurality of containers for articles of food, means to support said containers in said body portion, said body portion being adapted to contain a liquid, means for heating said liquid, said liquid being in contact with said containers, and a plurality of independently energizable heat radiating elements positioned in said lid and adapted to radiate heat on the upper portions of the food in said containers.

2. In apparatus of the character described, in combination, an oven, a plurality of containers adapted to contain articles of food, a support for said containers in said oven, said support and said containers dividing said oven into two sections, the lower section of said oven having liquid therein, portions of said containers extending into said liquid, heating elements for each of said containers positioned in the top portion of said oven, and means for heating said liquid.

3. In apparatus of the character described, in combination, an oven, a plurality of containers for articles of food, a support for said containers in said oven, a plurality of heating elements positioned in the lower part of said oven beneath said containers, a plurality of heating members positioned in the top portion of said oven above said containers, switch means for regulating the number of said heating elements and members to be placed in operation, and liquid means for conducting the heat from said elements in the lower portion of said oven to said containers.

4. In apparatus of the character described, in combination, an oven comprising a body portion and a lid, a plurality of containers for articles of food, means to support said containers in said body portion, said body portion being adapted to contain a liquid, means for heating said liquid, said liquid being in contact with said containers, and heat radiating means for each of said containers in said lid adapted to radiate heat upon the upper portions of the food in said containers.

5. In apparatus of the character described, in combination, an oven comprising a body portion, a plurality of containers for articles of food, means for supporting said containers within said body portion, said supporting means for said

containers forming a partition lying in a plane parallel to the bottom of said body portion and separating said body portion into two sections, a liquid substantially filling the lower part of said body portion, plate means dividing said lower part into separate sections, heating elements positioned in each of said sections, means to control the amount of heat given off by said heating means, and individual switch means for controlling each of said heating elements.

6. In apparatus of the character described, in combination, an oven comprising a body portion and a lid, a plurality of containers for articles of food, supporting means for said containers positioned within said body portion, said supporting means and said containers separating said body portion into two sections, the lower part of said oven being adapted to contain a liquid, plate means dividing said lower part into separate sections, individual heating elements for each of said last-mentioned sections, means to control the amount of heat given off by said heating elements, a plurality of heating members posi-

tioned in said lid, said last-mentioned heating members being positioned above said containers, and switch means for controlling the supply of current to said heating elements.

5 7. In apparatus of the character described, in combination, an oven, a plurality of containers for articles of food, a support for said containers within said oven, said support and said containers dividing said oven into upper and lower parts, a plurality of plates extending across said oven dividing the lower part thereof into a plurality of sections, individual heating elements for heating the liquid in each of said sections, controls for each of said elements, said plates preventing 15 free circulation of the liquid between said sections and also preventing wave motion of the liquid throughout the length of the oven when portions of said containers are submerged in said liquid, and radiant heating means positioned in 20 the top portion of said oven above said containers.

ROLAND W. WHITE.
